A. F. SHEPHERD.
FASTENING MECHANISM FOR DOUBLE DOORS.
APPLICATION FILED NOV. 16, 1914.

1,142,463.

Patented June 8, 1915.

UNITED STATES PATENT OFFICE.

ARTHUR F. SHEPHERD, OF COLUMBUS, OHIO.

FASTENING MECHANISM FOR DOUBLE DOORS.

1,142,463.

Specification of Letters Patent. Patented June 8, 1915.

Application filed November 16, 1914. Serial No. 872,308.

To all whom it may concern:

Be it known that I, ARTHUR F. SHEPHERD, a citizen of the United States, and resident of Columbus, in the county of 5 Franklin and State of Ohio, have invented certain new and useful Improvements in Fastening Mechanism for Double Doors, of which the following is a specification.

This invention relates to double doors or 10 doors used in pairs to close a doorway, one of the doors of the pair being provided with one or more vertical end bolts whereby it may be bolted to the door frame, and slotted or recessed at its outer edge to receive a lock 15 bolt, or a lock bolt and a latch bolt, on the companion door, so that the two doors may be interlocked.

The invention has for its object to prevent the doors from being interlocked until 20 the end-bolt-carrying door has been engaged with the door frame by its bolt or bolts, and thus prevent the possibility of insufficiently fastening the doors, it being a fact that if the doors are interlocked without bolting 25 one of the doors to the frame, they can in many cases be opened by pressure against their meeting edges.

The invention consists in the improvements which I will now proceed to describe 30 and claim.

Of the accompanying drawings forming a part of this specification: Figure 1 represents a vertical section of a portion of a door carrying two vertical end bolts, and provided with an attachment embodying my invention, the bolts being retracted, and portions of the companion door shown by dotted lines; Fig. 2 represents a view similar to Fig. 1, showing the end bolts projected; Fig. 3 represents an elevation of the inner side of the baffle hereinafter described; Fig. 4 represents an edge view of a portion of the end-bolt-carrying door; Fig. 5 represents a section on the plane indicated by 45 the broken line 5—5 (Fig. 1) and a top plan view of the parts between the divisions of said line; Fig. 6 is a sectional view showing the part hereinafter termed the baffle, adapted to serve also as a striker plate.

50 The same reference characters indicate the same or similar parts in all the views.

In the drawings, 12 represents a portion of the end-bolt-carrying door of a pair of doors, and 13 represents a portion of the 55 companion door, the latter being shown by dotted lines (Figs. 1 and 2).

The door 12 is provided with vertical end bolts 14 adapted to enter sockets in the door frame top and in the sill or threshold. Said bolts are simultaneously projected and retracted by a manually operated member which is preferably composed of a spindle 15 having circular end portions journaled in bearings 16 attached to the door 12, and oppositely projecting arms 17 formed on a 60 hub 17^a engaged with the squared central portion of the spindle. Said arms are connected with the bolts 14 by elongated rods 18 having terminals 20 pivoted at 19 to the arms, the outer ends of the rods being 65 threaded and engaged with tapped orifices in the bolts. One end of the spindle is provided with a handle 21 by which it may be turned.

The companion door 13 is provided with 70 the usual latch bolt 23 and lock bolt 24, these being arranged to enter slots 25 and 26 in a striker plate 27 attached to the edge of the door 12, the doors being thus interlocked, as indicated by Fig. 2.

80 28 represents a baffle which is vertically movable on the edge portion of the door 12, and is so formed and so connected with the manually operated bolt throwing member that when the end bolts 14 are retracted the 85 baffle stands in the paths of the latch and lock bolts 23 and 24, as shown by Fig. 1, and prevents the interlocking of the doors. When, however, the end bolts are projected, the baffle is moved out of the paths of the 90 bolts 23 and 24, and permits the interlocking of the doors, as shown by Fig. 2.

95 The baffle is preferably a plate fitted to slide vertically in a guideway in the edge of the door 12, behind the striker plate 27, and is preferably provided with a slot 29 formed to receive the latch bolt 23, and with a slot 30, formed to receive the lock bolt 24. The portions of said plate between the slots 29 and 30, and below the slot 30, constitute 100 the acting portions of the baffle and stand in the paths of the bolts 23 and 24 when the end bolts are retracted.

105 The preferred connections between the manually operated end-bolt-throwing member and the baffle whereby the baffle is caused to act automatically as above stated comprise spaced apart ears 32 on the inner side of the baffle, and a tappet 33 on one of the arms 17 engaged with the ears 32.

110 It will be seen by reference to Figs. 1 and 2 that when the end bolts 14 are retracted

the baffle 28 covers the striker plate slots 25 and 26, and prevents the interlocking of the doors, and that when the end bolts are projected the baffle uncovers said slots, so that 5 the slots or recesses 29 and 30 of the baffle receive the bolts 23 and 24. The doors can therefore be interlocked only when the end-bolt-carrying door 12 is secured to the door frame.

10 The striker plate 27 constitutes a convenient means for guiding the baffle 28, and retaining it on the door 12. It is obvious however that the baffle formed to receive the projected bolts 23 and 24 constitutes 15 also a movable striker plate, which may be exposed on the outer surface of the door 12 and guided and retained on the door by any other suitable means, as shown by Fig. 6.

I do not confine myself to the specific 20 construction of the end bolt throwing mechanism, the baffle, and the connections between the baffle and the manually operated bolt throwing member, and these may be variously modified without departing from 25 the spirit of the invention. Moreover, it is obvious that the baffle may be apertured to coöperate with but one bolt on the door 13, the bolt 24 for example, and that the door 12 may be provided with one end bolt 14 instead of two.

30 Incidentally the baffle prevents the end bolts from being retracted while the doors are interlocked. The attachment may be secured to the exterior of the door in an exposed position, instead of being inclosed between the sides of the door as here shown.

Having described my invention, I claim:

1. An attachment for one of a pair of 40 doors, comprising a manually operated end-bolt-throwing member mounted on said door, a baffle movable on the edge portion of the same door and apertured to receive a lock bolt on the companion door, means being provided for confining and guiding 45 said baffle, and connections between said bolt throwing member and baffle, whereby a movement of said member to its end bolt retracting position locates said baffle in the path of the said lock bolt to prevent the interlocking of the two doors, said baffle being formed to receive the said lock bolt and permit the interlocking of the doors when the said member is in its end bolt projecting position.

50 2. An attachment for one of a pair of doors, comprising a manually operated spindle journaled in bearings on the door and oppositely projecting arms on said spindle connected with end bolts at the upper and 60 lower ends of the door, one of said arms being provided with a tappet, and a baffle

movable on the edge portion of the same door and apertured to receive a lock bolt on the companion door, said baffle having ears engaged with said tappet and being movable 65 by the latter into and out of the path of said lock bolt, means being provided for confining and guiding said baffle.

3. An attachment for one of a pair of doors, comprising a manually operated end-bolt-throwing member mounted on the end-bolt-carrying door, a baffle movable on the edge portion of the same door and apertured to receive a lock bolt on the companion door, a striker plate attached to the end bolt-carrying door, and apertured to receive 75 said lock bolt, said plate constituting a means for confining and guiding said baffle, and operating connections between said bolt throwing member and baffle, said baffle being formed to alternately cover and uncover the apertures in the striker plate.

4. An attachment for one of a pair of doors, comprising a manually operated end-bolt-throwing member mounted on the end-bolt-carrying door, a baffle movable on the edge portion of the same door and apertured to receive a lock bolt and a latch bolt on the companion door, means being provided for confining and guiding said baffle, and operating 80 connections between the said member and baffle, whereby the baffle may be held alternately in the paths of said lock and latch bolts to prevent the interlocking of the doors, and out of said paths, the baffle 85 being formed to receive the lock and latch bolts and permit the interlocking of the doors.

5. An attachment for one of a pair of doors, comprising a pair of bearings attached to said door, a manually movable spindle journaled in said bearings, oppositely projecting arms on said spindle, end bolts at the upper and lower ends of the door, rods connecting said bolts with the 105 spindle arms, a baffle movable on the edge portion of the door and apertured to receive a locking bolt and a latch bolt on the companion door, operating connections between said baffle and one of the spindle 110 arms, and a fixed striker plate also apertured to receive said locking bolt and latch bolt, said baffle being formed to alternately cover and uncover the apertures in the 115 striker plate.

In testimony whereof I have affixed my signature, in presence of two witnesses.

ARTHUR F. SHEPHERD.
